C. MACUMBER

SCREED ANCHOR

Filed Nov. 29, 1922

Inventor
Clarence Macumber

by *Dwight Hague Atlys*

UNITED STATES PATENT OFFICE.

CLARENCE MACUMBER, OF WINTERSET, IOWA.

SCREED ANCHOR.

Application filed November 29, 1922. Serial No. 604,010.

To all whom it may concern:

Be it known that I, CLARENCE MACUMBER, a citizen of the United States, and a resident of Winterset, in the county of Madison, 5 State of Iowa, have invented a certain new and useful Screeed Anchor, of which the following is a specification.

My invention relates to that class of screed anchors which are intended to be forced or 10 driven into concrete before it has set and hardened, and then after it has set and hardened, the upwardly projecting ends may be bent over flat against the top surface of the concrete so that the anchors will not 15 interfere with the use of the concrete base during further building operations, and then when it is desired to lay a wooden floor on a concrete base, the portions of the anchors above the concrete may be bent upwardly 20 and secured by nails or otherwise to opposite sides of the screeds, and finally the wooden floors may be secured to the screeds.

With screed anchors of this type now in general use, there is at times considerable 25 difficulty in getting them to penetrate the mass of concrete, and at times it is necessary to take a mallet or hammer and drive them into position, and in this connection it is one of my objects to provide a screed 30 anchor which will readily and easily penetrate the mass of concrete and which is so shaped and proportioned, and made of such material, that it may be driven with a mallet or hammer straight into the mass of concrete. 35

Heretofore it has been customary to provide screed anchors having the portion thereof that penetrates the concrete made corrugated or with divergent parts for the 40 general purpose of forming a better anchorage in the concrete after it has set. With devices of this kind, and in instances where it is necessary to use considerable force or to hammer them into the concrete, they will, 45 in many instances, instead of penetrating straight into the mass of concrete, strike a stone or other obstruction in the mass and bend laterally, and hence not become properly embedded in the concrete so that after 50 they are in use and strains are applied to them, they will pull out of the concrete and thus result in defective anchoring of the screeds; and in this connection it is my object to provide a screed anchor which,

when being driven into the mass of concrete, 55 will penetrate straight down into the mass and move aside or press down any such obstructions, as a relatively large stone, without deflecting the downward path of travel of the screed anchor. 60

Another object of my invention is to provide a screed anchor of this character with anchoring members formed in the lower ends of the upright members and inclined upwardly and away from the upright members, whereby there is presented in the lower or penetrating end of the anchor a smooth round and penetrating point that will tend to slide over stones or similar obstructions in the mass of concrete and push them aside, thus making it relatively easy to force the anchors into the mass of concrete, and also to form a more perfect and secure anchorage after the concrete has set and hardened. 65 70

A further object is to provide an anchor of this character having anchoring means at the horizontally arranged connecting member of the anchor to thereby prevent this connecting member from being broken away from the concrete when the upwardly projecting ends of the anchors are purposely or accidentally bent from their upright positions. 75 80

My invention consists in the construction, arrangement and combination of the various parts of the device, whereby the objects contemplated are attained, as herein-after more fully set forth, pointed out in my claims, and illustrated in the accompanying drawings, in which: 85 90

Figure 1 shows a perspective view illustrating my improved screed anchor.

Figure 2 shows a vertical, sectional view through a portion of a concrete base and a wooden screed thereon with one of my improved anchoring devices applied thereto as in use. 95

Figure 3 shows a vertical, sectional view through a portion of a concrete base and a side elevation of a portion of a wooden screed thereon with my improved anchor applied thereto as in use; and 100

Figure 4 shows a side elevation of a modified form of my invention.

Referring to the accompanying drawings it will be seen that my improved screed anchor is formed complete with a single length of round wire and this wire is pref- 105

erably made of relatively stiff material adapted for driving, as will hereinafter be more fully explained. The central portion of the wire forms the connecting member indicated by the numeral 10. At the central portion of this connecting member there is a downwardly extending anchoring loop 11. At the sides of the connecting member are the upright members 12 which extend upwardly to a distance somewhat less than the height of the screed to be placed thereon, and the space between the upright members 12 corresponds with the width of the screeds to be used. 15 At the top of the upright members 12 the wire is bent in a half circle at 13 and then extended straight downwardly forming the upright anchoring members 14. The parts 12 and 14 stand slightly spaced apart 20 from each other, the space between them being sufficiently large to receive nails 15. At the lower ends of the anchoring members 14, the wire is given a sharp bend upwardly and away from the part 14 to form the anchors 16 and also the rounded penetrating ends 17. The screeds shown in Figures 25 and 3 are indicated by the numeral 18.

In the modified form of my invention shown in Figure 4, I use the same upright anchoring members 14 having the anchors 30 16 at their lower end, and the half turned end 13 at the top, but the part indicated in Figure 4 by the numeral 19 extends parallel with the part 14 down to a point adjacent 35 to the lower end of the part 14.

When this form of the invention is used, these anchors are arranged on a screed in staggered relation. That is to say, one is first placed on one side of the screed and 40 then the next one on the opposite side of the screed and so on throughout the length of the screed.

In practical operation and after the concrete base has been placed in position and 45 leveled off, and before it has set and hardened, the anchors are placed therein in upright positions along lines designed to receive a screed between the upwardly projecting portions of the anchors. In some 50 instances these anchors penetrate the mass of concrete easily, but in many instances where the concrete is relatively stiff or consists principally of relatively large stones, it is necessary to press the anchors with 55 considerable force into the concrete, and sometimes it is necessary to take a mallet or hammer and drive the anchors into place. When this heavy pressing or driving operation is necessary, the peculiar shape of the 60 anchoring member 16 is of greater advantage because the penetrating point is smooth and rounded and will tend to press to one side the large stones in the concrete and in addition to this, if these stones have 65 been pressed aside and the anchor driven

to position below them, the concrete that was thus pressed will tend to expand and the stones moved back to position directly above the anchoring member 16. This is 70 illustrated in Figure 3, and when this occurs then a very strong and firm anchorage is provided.

In screed anchors in which the concrete penetrating member was made corrugated, then when such anchors are forced into the 75 concrete, the large stones were pressed to one side, and away from the path and out of contact with the anchor, and no stones could, of course, assume a position directly above the anchoring member such as the member 80 16. Hence by my improvement, I have provided an anchoring device of this character which may be driven into concrete with a mallet or hammer, and when so driven, the penetrating ends will pass straight through 85 the mass of concrete and after it has passed through the concrete and stones will assume a position directly above the anchoring member and thus add additional strength to the structure. Whereas, in screed anchors 90 where the penetrating ends are either corrugated or made slightly divergent from a straight line, it frequently happens that in driving or pressing them into concrete they turn out laterally and only penetrate the 95 concrete a short distance, and then when strains are applied to them, later they pull out.

The anchoring member 11 on the connecting member 10 serves a valuable and important function in that when the anchor is placed in the concrete as shown in Figure 2, this anchoring member will hold the connecting member firmly in its position, and the necessity for this occurs when the concrete floor has set and hardened and workmen are using the concrete floor during further building operations, then the upwardly projecting ends of the anchors are bent over flat with the floor and this anchoring member 11 prevents the connecting member 10 from being broken loose from the concrete during such movements of the anchor. 105

I claim as my invention:

1. An improved screed anchor comprising 110 a member designed to be secured to both sides of a screed and two anchoring members connected therewith, and designed to extend into concrete, and a third anchoring member connected to the part of the anchor 115 that receives the screed and designed to penetrate the concrete a short distance between the other anchor members, for the purposes stated. 120

2. An improved screed anchor formed of 125 a single piece of round and relatively stiff wire and comprising a connecting portion, an anchoring loop formed in the connecting portion and designed to penetrate the concrete, two upwardly extended members at 130

the opposite ends of the connecting member, two straight downwardly extended members at the ends of said upwardly extending members and designed to project a considerable distance below the connecting member, there being loops formed between the said upwardly and downwardly extending

members to receive nails, and an anchoring member at the lower end of each of the downwardly extended members extended 10 upwardly and outwardly, for the purposes stated.

Des Moines, Iowa, November 27, 1922.

CLARENCE MACUMBER.
